UNITED STATES PATENT OFFICE.

WILLIAM GEORGE CRESSWELL, OF BECKENHAM, CHRISTCHURCH, NEW ZEALAND.

LIFTING OF PLOWS.

1,355,815.

Specification of Letters Patent. Patented Oct. 19, 1920.

Application filed January 7, 1918. Serial No. 210,791.

To all whom it may concern:

Be it known that I, WILLIAM GEORGE CRESSWELL, a subject of the King of Great Britain, residing at 36 Tennyson street, Beckenham, Christchurch, in the Dominion of New Zealand, have invented new and useful Improvements in and Relating to the Lifting of Plows, of which the following is a specification.

10 This invention relates to plows, and although specially adapted for use in conjunction with tractors, is applicable also to horse-drawn implements.

Hitherto, various means have been devised 15 for enabling the plow to be lifted out of the furrow when desired, as for instance, when turning at the head-lands. These means, however, although capable of operating satisfactorily in land of an even and regular 20 nature, have proved impracticable for use where large stones and other obstructions are encountered.

It is the object of the present invention, therefore, to provide a novel construction 25 for this purpose capable of operating quickly with a regular and positive action in any class of land.

In carrying this object into effect, the invention consists essentially in obtaining the 30 necessary power for the lift from the rotation of the land-wheel of the implement.

In order that the nature of the invention may be fully understood, reference will now 35 be made to the accompanying sheet of drawings in which:—

Figure 1 is a perspective view of a portion of a plow showing, by way of example, one practical method of applying the invention,

40 Fig. 2 is also a perspective view of a portion of such plow as viewed from a position in front of the implement, and,

Fig. 3, is a plan view of the land-wheel 45 illustrating in detail the means of carrying out the invention as already shown in the preceding figures.

Fig. 4 is an enlarged detail view showing a portion of the apparatus shown in the preceding views.

50 Fig. 5 is a sectional view, taken on the line V—V of Fig. 4 and looking in the direction of the arrows.

1 is the plow which may be of any of the 55 types at present employed for performing various kinds of work and provided with the usual land-wheel 2.

As here shown, the land-wheel is mounted by means of a cranked axle 3 carried in bearings in the plow-frame so as to enable the lifting of the plow-frame to be effected 60 by turning or rocking the axle. As this is the customary construction embodied in most plows and has been adopted almost universally as being probably the simplest and most practical method of performing 65 this purpose, the present invention, in order that it may be fully understood and appreciated by those skilled in the art to which it relates, is herein described and illustrated in its application thereto. It must be clearly 70 understood, however, that the invention is not confined to any such combination with this or any other known feature of plow construction, but includes within its scope, as hereinbefore mentioned, a means for obtaining 75 from the rotation of the land-wheel the power necessary for lifting the plow-frame, which power may be applied in any suitable manner.

According to the present invention, a 80 drum 4 is provided and revolvably mounted upon the axle 3 adjacent to the land-wheel 2, clutch means being provided to enable the said drum to be brought into engagement with, so as to be rotated by the land-wheel 85 or thrown out of engagement therewith.

As here shown, this purpose is effected by making the drum 4 slidable upon the axle and providing the outer face of such drum, that is the face adjacent to the land-wheel 90 with one or more projections 5 adapted when such drum is caused to approach the land-wheel, to be engaged by the spokes of the latter. In lieu of this simple construction, however, any other form of clutch may be 95 employed to place the drum in or out of gear with the land-wheel.

For the purpose of operating the said clutch means, suitable striking gear is provided. As here shown, this striking-gear 100 comprises a rod 6 slidable in guides 7 carried upon the axle 3, such rod being provided with a fork 8 adapted to engage a groove 9 formed in the boss of the drum 4. For the purpose of operating the rod 6, a 105 shaft 10 is provided and arranged to extend upwardly in bearings 11 carried upon the axle 3. Upon the lower end of the said shaft 10 is provided an eccentric-plate or cam 12 adapted to engage between plates 110 or collars 13 upon the rod 6, while upon the upper end of the shaft 10 is mounted

a crank or lever 14 capable of being operated by means of a cord 15 (Fig. 2) from the tractor or from the driver's position in the case of a horse-drawn implement.

- 5 Attached to the said drum 4 is one end of a chain or other flexible connection 16 which is led around a sheave-block 17 mounted at a suitable point upon the plow-frame in rear of the land-wheel, and 10 from whence such chain is led forward again and attached at its other extremity either to the cranked portion of the axle 3, or, as here shown, to a suitable extension or arm 18 provided thereon.
- 15 For the purpose of locking the axle 3 in the required position to retain the plow-frame in the raised condition, the usual hand-lever 19 is provided, such hand-lever having a detent 20 adapted to engage in a 20 notch 21 provided in a quadrant 22 as customary. Upon the hand-lever 19 is provided a short lever 23 adapted to release the said detent when operated as by means of a cord 24 connecting it with the tractor or 25 the driver's position in the case of a horse-drawn implement.

In operation, when the plow is performing its work, the clutch will be in the disengaged condition and consequently the 30 land-wheel will be free to revolve without the drum. When it is desired to lift the plow, however, the trip or striking gear is operated by placing a tension upon the cord 15, thus causing the clutch to come into 35 operation and so connect the drum 4 with the land-wheel. As the implement continues to travel in this condition, the land-wheel will cause the drum to rotate and so wind around its periphery the chain 16. 40 The tension so placed upon the chain, will, by reason of the fact that the other end of such chain is attached to the arm 18 upon the cranked axle 3, cause such axle to turn and in consequence, raise the plow-frame 45 in the well-known manner.

Provision is made also for causing the clutch to automatically release the drum from engagement with the land-wheel upon the plow-frame being raised to the required 50 extent. As here shown, such means comprise a chain or other connection 25 of the required length attached at one end to the lever 14, while its other end is attached to the plow-frame at a suitable point as 26 in 55 rear of the axle 3. By this arrangement, while the plow-frame is in the lower or operative position, the chain 25 will be slack, as shown in Fig. 1, and will therefore permit of the lever 14 being operated when 60 desired by means of the cord 15. In consequence of the fact that the shaft 10 is mounted upon the axle 3 however, it will be understood that the turning of the latter in the operation of raising the plow-frame, 65 as already explained, will increase the dis-

tance between the lever 14 and the point 26, thus drawing the chain 25 into tension. The length of the chain 25 is such as to permit the raising to continue until the detent 20 comes into engagement with the notch 21, 70 whereupon such chain becoming taut, will serve to return the lever 14 to its original position, and so cause the striking gear to disengage the clutch and release the drum, the plow-frame being retained in the upward condition solely by the engagement of the detent 20 in the notch 21. In order to make this releasing action of the clutch as quick and positive as possible, a spring 27 may be provided, the tendency of which is 80 to carry the rod 6 into the disengaged position.

The plow frame, having been thus raised, and the clutch thrown out of gear, it will be understood that the drum 4 being free upon 85 the axle, will permit the chain to become slack and so allow of the plow-frame again resuming its downward or operative position when the detent of the land-lever is released from the notch by the action of placing a tension upon the cord 24. In cases where there is a tendency on the part of the land-wheel to skid in consequence of its grip upon the surface of the land being insufficient to effect the rotation of the drum, the 95 periphery of such wheel may be provided with suitable studs 28, as shown in Figs. 1 and 2.

If so desired, this method of lifting may be applied so as to cause the plow-frame to 100 rise on any or all of its wheels simultaneously with the lifting upon the land-wheel. This purpose may be effected in a variety of different ways as for instance, in cases where the wheels are mounted by 105 means of an upwardly extending stem received within guides in the plow-frame, as is the common practice, levers or chains may be employed to cause the stem to slide in its guides and so vary the height of the plow 110 frame, such levers or chains being controlled and operated by the axle 3 or directly by the chain 16.

It will be obvious also that should the land-wheel itself be mounted in a similar 115 manner by means of a stem slideable in guides in the plow-frame, in lieu of the cranked axle, the pull of the chain 16 may be applied so as to cause the plow-frame to rise upon the stem.

As hereinbefore explained, however, these known details of plow construction are dealt with in the present specification merely by way of illustration in order that the invention may be the better understood from a 12 consideration of some possible methods of applying it.

I claim:—

In a plow of the type described comprising a plow-frame, plow means rigidly 13

mounted thereon, a land-wheel, a cranked axle therefor adapted to be turned for the purpose of raising or lowering the said plow-frame in relation to the land-wheel, 5 means for maintaining the plow-frame in the raised condition, a drum revolvably mounted upon the said cranked axle and slideable thereon into and out of engagement with the land-wheel, and a chain adapted to 10 turn the cranked axle thereby to raise the plow-frame, of a rod disposed parallel with said movement of the drum and slideable in guides carried upon the cranked axle, a fork carried upon said rod and adapted to engage within a circumferential groove formed around the boss of the said drum, a pair of 15 collars mounted upon said rod at a suitable interval apart, a shaft carried in bearings

upon the cranked axle and disposed at right angles with said rod, an eccentric or cam 20 carried upon the lower end of said shaft and adapted to engage between said collars, a crank or lever mounted upon the upper end of the shaft and adapted to cause the drum to engage the land-wheel and a connecting member extending between the said crank of the shaft and a suitable fixed point 25 upon the plow.

In testimony whereof I have hereunto set my hand in the presence of two subscribing 30 witnesses.

WILLIAM GEORGE CRESSWELL.
